 a corporation of Connecticut

Application August 10, 1945, Serial No. 610,068

3 Claims. (Cl. 24—205.13)

1

This invention relates to the manufacture of separable fasteners of the type having flexible supports provided on the opposed edges thereof with cooperating series of locking elements adapted to be progressively interlocked or disengaged by means of a manually operated slider.

In fasteners of the type indicated, the locking elements are usually formed with two ends or jaws by which they are connected to the flexible supports. Heretofore, the locking elements have been usually secured in position on the supports either by clamping the ends or jaws thereof, to the fabric material of the supports, or by causing such ends to pierce the material of the supports and then compressing them thereon, or by adhesively connecting such ends to the supports. A disadvantage of clamping or compressing the ends of the elements onto the supports, is the likelihood of the fabric fibers being crushed or cut by the material, of the elements, thus weakening the supports. On the other hand, adhesively connecting the elements to the supports is likely to soil and stiffen the latter. Furthermore, whether the element is clamped, compressed or adhesively secured by its ends or jaws to the support, such attachment of the element to the support is no stronger than its bond thereto, and it has not been an uncommon occurrence for an element so attached, to be shifted or loosened or even torn from its anchorage through usage, thereby rendering the entire fastener structure inoperative.

The principal purpose of the present invention is to improve the manufacture of separable fasteners so that they will not possess the above disadvantages and more particularly, to attach the elements to the supports so that they will be positively and securely fixed in position and so that the bond therebetween is as strong as the material of which the support is constituted.

Another object of the invention is to provide an improved fastener structure having advantages of construction and operation over prior fasteners of this type, and which can be manufactured without waste and economically in large quantities.

Other objects and advantages of the invention as well as the novel features thereof will become apparent after a perusal of the following description when read in connection with the accompanying drawings in which Fig. 1 is a longitudinal sectional view of the die mechanism for manufacturing the fastener of this invention, the view being taken along the line 1—1 of Fig. 2 and illustrating an intermediate step in the

2

formation of the element on the support; Fig. 2 is a front elevational view of the die mechanism shown in Fig. 1; Fig. 3 is an enlarged elevational view of a portion of the die, the view being a central sectional view of the female die parts as is indicated by the line 3—3 in Fig. 4 of the drawings and illustrating the step of forming the interlocking end of the locking element; Fig. 4 is a vertical sectional view showing in enlarged detail, the construction and arrangement to the die mechanism; Fig. 5 is a sectional view of a support illustrating an initial step in forming a locking element thereon, in accordance with this invention; Fig. 6 is a similar view showing the locking element after the first bending operation; Fig. 7 is a similar view showing the locking element after its ends have been compressed or bent together as a result of closing the die; Fig. 8 is a view similar to Fig. 7 and shows the form 10 of the finished element after it has been subjected to the dieing operation illustrated in Figs. 3 and 4, the element being shown with its locking recess upward, and Fig. 9 is a similar view showing the completed element with its locking projection upward.

In the drawings, the reference numeral 10 designates the supports of the fastener. The supports 10 are flexible and are preferably made of fabric tapes having beaded edges 11 around which the locking or fastener elements 12 are formed (see Figs. 8 and 9). The locking elements are arranged along the beaded edges of the two supports of the fastener in uniformly and accurately spaced relation and in such manner that the elements of one support may be brought into interfingered relation with the elements of the other support or disengaged from such interfingered engagement by a slider (not shown) which is manually operated through a pull tab.

In one desirable embodiment of the invention, the locking elements 12 are made from round wires or filaments bent upon themselves about the beaded edges 11 of the supports 10 to provide an integral, link-like attaching portion and two end portions which are formed into the locking end of the element. As is shown in Fig. 5 of the drawings, the section of round wire or filament 13 which is to form the locking element, is inserted through the flexible support 10 just back of the beaded edge 11 of the support so that its ends extend equal distances from each side of the support. The length of the wire 13 is such that when the two ends are bent about the bead 11 in the manner to be described, there will be

sufficient material to form a locking element of the desired size. The initial bending of the wire 13 is illustrated in Fig. 6 of the drawings, the wire 13 after this operation having a substantially U-shaped configuration and its ends 14 projecting forwardly beyond the beaded edge 11 of the support 10. The wire 13 is then squeezed to clamp it securely in position on the beaded edge 11 and at the same time, to bring together into close side-by-side relation, the projecting portions or ends 14 thereof. This step in the formation of the locking element is illustrated more clearly in Fig. 7 of the drawings which shows that the end portions have been moved from their spaced condition without disturbing their substantially parallel relation so that there is no space between such two end portions throughout their lengths. The projecting end portions 14, 14 of the wire 13 are then subjected to a dieing operation to give them the form shown in Figs. 8 and 9 of the drawings, wherein such end portions are provided with a locking recess 15 and a locking projection 16. The wire 13 utilized in the formation of the element may be constituted of any suitable material capable of forming satisfactory elements. When a metal wire is used, it is preferred that it be of dead soft brass as this material is not only readily workable but also possesses the advantage that it hardens as it is worked. When the wire or filament used is constituted of a plastic material, the operations on such wire in the formation of the element, may be carried out with the use of heat, as is well-known in the art.

The formation of the wire section 13 into the finished locking element illustrated in Figs. 8 and 9 of the drawings, may be accomplished readily by the die mechanism illustrated in Figs. 1 to 4 of the drawings. The wire or filament 20 for forming the elements and from which sections like the wire section 13 are cut, may be drawn from a reel and fed to the die mechanism by either hitch or roll feed, a type of roll feed being indicated generally in Fig. 2 of the drawings by the intermittently operating feed rolls 19, 19. From the feed rolls 19, 19 the wire 20 passes into a longitudinal opening in a guide block 21 whose inner end 21' serves as a portion of a guideway for a forming tool 22 (note Figs. 1, 2 and 4). During the feed of the wire 20, the forming tool 22 is in retracted position so that the wire advances to a position where its advanced end comes into engagement with the stop or inner surface portion 23 of a guide block 24. During its travel to the stop surface 23, the wire 20 passes through an opening 25 which has been formed in the flexible support 10 of the fastener just in back of its bead 11 (note Fig. 3). The flexible support 10 is fed in a vertical direction downwardly and with a step-by-step motion, the support in such feed being guided so that it is positioned intermediate the inner end 21' of the guide block 21 and the stop surface 23 with the previously formed opening 25 therein in alignment with the feed of the wire 20. Thus, when the wire 20 comes into engagement with the stop 23, there will be disposed on both sides of the flexible support 10, equal length portions of the wire 20.

The opening 25 is formed in the support 10 during a pause in the step-by-step feed of the latter by means of a pin 26 provided on the inner end of a block 27 slidably mounted on the guide block 21 and in the longitudinal opening formed by the guide plates 28, 29 and 30. The

pin block 27 is provided with an actuating member 31 which projects upwardly through a slot 32 in the guide plate 28 (see Fig. 1) and is engaged by the forked end of an actuating lever 33 pivotally mounted at 34 on the die base 35. The lever 33 is connected to mechanism adapted to actuate it in a clockwise direction, as viewed in Fig. 1, during each pause in the intermittent feed of the flexible support 10. The longitudinal axis of the pin 26 is positioned directly over the longitudinal axis of the wire 20 fed through the guide block 21 and so related to the position of the support 10, that as it is advanced by the actuating lever 33 through member 31, it passes through the support just in back of the bead 11, as is shown more clearly in Fig. 3 of the drawings, to form the hole 25. In its advancement, the pin 26 enters a guide recess 36 formed in a projecting portion 37 of the guide block 24. The plates 28, 29 and 30 and guide block portion 37, thus, accurately position and guide the movements of the pin 26 relative to the flexible support 10. The distance between the longitudinal axis of pin 26 and the longitudinal axis of the opening in guide block 21 through which the wire 20 is fed, is exactly equal to the distance between the centers of attachment of the locking elements 12 formed on the support 10 and the step-by-step feed of such support is such that when the pin 26 has been retracted by the actuating lever 33 and the support 10 has been advanced in its next step-by-step movement, it will come to rest at the end of such movement with the hole 25 formed by the pin 26 in alignment with the feed of the wire 20.

After the advanced end of the wire 20 comes into engagement with the stop surface 23, it is subjected to cutting and bending operations to give it the form shown in Fig. 6 of the drawings. These operations are accomplished by the forming tool 22 which is reciprocated in directions transverse to the feed of the wire during the pauses in the step-by-step feed of the flexible support 10. The tool 22 is guided in its reciprocating movements by the guide blocks 21, 24, 28 and 30 and passes beneath the pin block 27 and the projecting portion 37 of block 24 in the region of its operation as is shown more clearly in Figs. 1 and 4 of the drawings. The working end of the forming tool 22 is fork-shaped to allow its end portions 40, 40 to pass on either side of the support 10 during the advancing movement of such tool without disturbing such support. Adjacent the forward ends of the portions 40, 40 the opposed side walls thereof, are concaved to enlarge the slot 41 therebetween into a substantially U-shaped form. Forwardly of such enlarged portion of the slot 41, the opposed side walls of the portions 40, 40 are inclined forwardly to provide the convexly-shaped bending surface portions 42, 42. It will thus be understood that as the forming tool is advanced during each pause in the step-by-step feed of the support 10 by suitable mechanism (not shown), the left hand end portion 40 thereof, as viewed in Figs. 1 and 4, coacts with the inner end of the guide block 21 to cut or sever the portion of wire 20 projecting beyond such block to form the wire section 13. The cut section 13 of wire (see Fig. 5) is then bent by the surface portions 42, 42 of tool 22 during their advancing movement about the bead 11 of the support 10. At this time, the punch 43 has been positioned in front of the bead 11 (see Figs. 1 and 3) and enables such bending operation to take

place about the bead by providing a rigid support for the latter against the force required to bend the wire section 13. As the forming tool 22 moves to its fully advanced position, the cut section of wire 13, bead 11 and punch 43 enter the enlarged end portion of the slot 41, at which time, the wire section 13 is completely bent into the U-shaped form shown in Fig. 6 of the drawings.

In the next step-by-step movement of the support 10, the U-shaped wire section passes between the spread die members 44, 44 which are slidably confined between two guide bars 45, 45 secured to the base 35 and are normally maintained in spread or open condition by the springs 46, 46 therebetween. In its feed, the support 10 passes between the springs 46, 46 as is shown in Fig. 1 of the drawings. The die members 44, 44 are provided at their outer, upper ends with beveled surfaces 47, 47 adapted to be engaged by the beveled surfaces 48, 48 provided on the inner lower ends of the die actuating members 49, 49 of the punch and cooperable to force the die members 44, 44 together against the tension of the springs 46, 46 in the advancement of the punch. When the die members 44, 44 are substantially closed, the body portions of the members 49, 49' pass between such die members and the back stop strips 50, 50 mounted on the die base 35. It will be noted that the left-hand die actuating member 49 as viewed in Figs. 1 and 2, is forked and straddles the guide block 21 extending transversely thereof. The die actuating members 49, 49' are integrally connected together at their upper ends by a bridging portion 51 which adjustably carries the punch 43, the whole being mounted on the lower end of a punch actuating rod 52 which is connected to intermittently actuating mechanism, not shown.

The inner opposed ends of the die members 44, 44 are each provided with one-half of the die female 53, which, when the die members 44, 44 are closed, is so formed as to give the end portions 14 of the bent wire section 13, the conformation shown in Fig. 7 of the drawings. When the punch 43 then descends, the locking recess 15 and the locking projection 16 is formed, giving to the projecting ends 14 of the wire section 13, the conformation shown in Figs. 8 and 9 of the drawings. Provided below the die 53 is a recess 54 formed when the die members 44, 44 are closed and adapted to receive a previously formed locking member, the inner or upper wall of such recess 54 being spaced from the lower surface of the die 53, a distance exactly equal to the spacing between the surfaces of the elements engaging said parts in the finished fastener. The recess 54 communicates with an enlarged opening 55 in the die mechanism through which the finished support or stringer is fed.

From the foregoing, it will be understood, that when the support 10 is ready to advance on its next step-by-step movement during its feed through the machine, the forming tool 22 and pin 26 will be retracted, the punch 43 will be raised and the die members 44, 44 will be held open or separated under the tension of springs 46, 46. As the support 10 moves downwardly on the next step of its feed, the open hole 25 therein formed in the previous operation, moves into alignment with the longitudinal axis of the opening in guide block 21, the wire section 13 in the form shown in Fig. 6 of the drawings moves into the region of the female die members 53, 53 and the fastener

element 12 completed in the previous cycle of operations moves from between the die members 53, 53 into the region of the recess 54 formed between the die members 44, 44 in the latter's closed condition. When the support 10 has advanced to and pauses at the end of each step-by-step movement in the feed thereof, the actuating rod 52 of the punch, descends to bring the inclined surfaces 48 of the punch members 49, 49', into engagement with the beveled surfaces 47 of the die members 44. As the rod 52 continues its downward movement, the coacting surfaces 47 and 48 force the die members 44 together against the tension of the springs 46 to close the die 53. During the closing of the two female die members forming the die 53, the wire section 13 is changed by the squeezing action of such members from the form shown in Fig. 1 of the drawings to that shown in Fig. 7 of the drawings. The closing action of die 53 is completed when the surfaces 47 and 48 disengage and the inner surfaces of the punch members 49, 49' come into engagement with the side surfaces of the die members 44 to lock the latter in closed position. At the same time that this locking action occurs, the punch 43 comes into engagement with the projecting ends 14 of the bent wire section 13 positioned in the now closed die 53 to form the fastener element into its final shape (see Figs. 8 and 9). It will be noted from Figs. 1 and 3 of the drawings, that the punch 43 is in engagement with the outer edge portion of the bead 11 during its descending movement. Thus, the punch 43 forms a rigid backing for the bead 11 during the initial bending of the wire section 13 by the forming tool 22 to bring it into the shape shown in Fig. 6 of the drawings, as has been described. This operation takes place after the pin 26 has been advanced to pierce a hole 25 in the support 10 and when the punch 43 is in its fully advanced position and is pausing momentarily before being retracted.

It will be noted from the foregoing, that in the practice of the invention, there is no loss whatsoever from waste. The whole of each of the sections 13 that are cut off from the feed wire 20 goes into the manufacture of the locking elements and nothing remains from such sections to be discarded. Because of the manner in which the several parts of the forming mechanisms cooperate, the elements are accurately and precisely positioned on the support 10 in a continuous and successive fashion, thus making it possible for the stringers to be manufactured at a minimum of cost and in large quantities. Due to the fact that the locking elements are each formed of an integral piece of metal about the bead 11 of the support 10, such elements cannot be pulled off the support without the fabric material of the latter first being destroyed. In this manner, the locking elements 12 are permanently fixed to the support so that their connection therewith is no longer the weakest part of the structure. In other words, where in prior fastener supports or stringers the strength thereof was no greater than the strength of the bond between the locking elements and the support, in the fastener structure of this invention, the strength is at least as great as the strength of the material of the support and the bond of the elements to such support is greater than the structural strength of the latter. This feature is of material importance in these devices, because, the greatest stresses that they encounter while in use, are those stresses which tend to pull

or rip the locking elements from their supports or the positions thereon to which they have been affixed.

The locking elements in themselves possess many advantages over known types of elements. It will be observed from the views thereof, in Figs. 3, 4, 8 and 9 of the drawings, that each locking element has a round configuration, i. e., the exterior surfaces of the U-shaped base or root thereof, is rounded both longitudinally and transversely and continue in an uninterrupted manner into the exterior surfaces of the locking portion which is also of a substantially round configuration. (Note the rounded, somewhat triangular form of the locking portion as is best shown in Figs. 3 and 4 of the drawings.) This rounded configuration of the locking elements makes them smooth to handle, minimizes the danger of the elements catching in fabrics, and obviates any danger to the person of the user, being smooth of feel to the wearer's skin. This configuration of the locking elements has the added advantage that in the operation of a slide fastener provided with such locking elements, the elements will not cut into the material of the slider as is the tendency of known types of locking elements which renders the slider in time loose and less efficient in operation. The rounded shape of the elements around the bead 11 of the support 10 assures that they will not crush or destroy the fibers of the support, whereby the material of the support is not weakened as is the case in those fasteners in which the locking elements are clamped in position on the supports. It will be noted also from a comparison of Fig. 7 with Figs. 8 and 9 of the drawings, that in the completed element, the material of the ends 14, 14 have been worked as a result of the dieing operation, so that they form a unitary locking portion in which the wall forming the locking recess 15 and pin 16 is relatively thin. Thus, the size of the wire sections used, can be picked to make locking elements of standard sizes but of less weight than locking elements of comparable sizes made according to other methods. As a result of the dieing operation also, the material of such ends 14, 14 is worked so that the sides of the resulting locking portion are substantially in alignment with the sides of the U-shaped base or root thereof and form a continuation of the round exterior surfaces of the latter (note Figs. 4 and 8). It will be noted also that as a result of the dieing operation, the two end portions 14, 14 have been in effect, welded or integrally bound together along the longitudinal center line of the element with portions of both ends forming the locking recess 15 and pin 16. The recess 15 is relatively broad and has a substantial depth, while the locking pin 16 which extends from the rounded front and side surfaces of the locking portion of the element, is somewhat shallower, thus providing in the interlocked elements, an extremely flexible connection. This flexibility is enhanced by means of a depressed line or recess 56 extending transversely of the element immediately in back of the locking pin 16 (note particularly Fig. 9) and formed by the portions 57 of the die 53 and the shoulder 58 of the punch 43 during the dieing operation (note Fig. 3). When the fastener elements are interlocked in a slide fastener, the depressed line or recess 56 will enable the elements to rock on themselves, thus making the fastener extremely flexible.

From a manufacturing standpoint, the locking elements of this invention also possess certain advantages over prior known elements, particu-

larly those prior elements which are formed by a die-cutting operation. As a result of such an operation, burrs and other irregularities are formed on the elements and it is accordingly necessary after the elements are formed, to subject them to mechanical brushing and deburring processes. A fastener element made according to the instant invention however, would not have to be so processed, for any burrs or irregularities which might have formed on the ends of the wire section 13 as a result of the cutting operation, would be entirely eliminated by the working of such ends during the carrying out of the dieing operation. Thus, the practice of the present invention effects a substantial saving in the cost of manufacturing the elements by entirely eliminating the need for such processes. Not only is the cost of such processes removed, but the elements produced by this invention will be much smoother than it would be possible to make die-cut elements with a brushing operation. This results in the production of a fastener in which the slider will have a freer action than the slider on a fastener which includes brushed, die-cut elements.

While I have described and illustrated a preferred form of my invention, it will be understood by those skilled in the art, that many changes and modifications may be made therein, without departing from the spirit of the invention or the scope of the appended claims.

I claim:

1. A slide fastener comprising a pair of flexible stringers having opposed series of spaced locking elements adapted to be progressively engaged and disengaged, each of said elements being composed of a wire section formed about a longitudinal edge of a stringer so as to entirely enclose a portion of such edge, and including a closed loop-shaped attaching portion extending through the stringer adjacent to such edge and enclosing such edge portion, and including a locking portion projecting outwardly from such edge, the opening in said attaching portion having an area less than the cross sectional area of said longitudinal edge intermediate the elements, and said locking portion being constituted and consisting of straight equal length end portions of said wire section arranged in contacting side-by-side relation, the combined material of both such wire end portions being worked to provide a unitary, integral locking portion having a locking projection on one side and a recess on the opposite side, the said projection and recess being formed in part from each of said wire end portions.

2. A slide fastener comprising a pair of flexible stringers having opposed series of spaced locking elements adapted to be progressively engaged and disengaged, each of said elements being composed of a wire section formed about a longitudinal edge of a stringer so as to entirely enclose a portion of such edge, and including a closed loop-shaped attaching portion extending through the stringer adjacent to such edge and enclosing such edge portion, and including a locking portion projecting outwardly from such edge, the opening in such attaching portion having an area less than the cross sectional area of said longitudinal edge intermediate the elements, and said locking portion being constituted and consisting of straight, equal length end portions of said wire section arranged in contacting side-by-side relation, the combined material of both such wire end portions being worked to provide a unitary, integral locking portion having a locking projec-

tion on one side and a recess on the opposite side, the said projection and recess being formed in part from each of said wire portions, the width of said locking portion being greater than twice the width of said wire in the loop-shaped attaching portion of said element and approximately the same as that of said loop-shaped attaching portion in the region of said longitudinal edge.

3. A slide fastener comprising a pair of flexible stringers having opposed series of spaced locking elements adapted to be progressively engaged and disengaged, each of said elements being composed of a wire section of round cross sectional area and formed about a longitudinal edge of a stringer so as to entirely enclose a portion of such edge, and including a closed loop-shaped attaching portion extending through the stringer adjacent to such edge and enclosing such edge portion, and including a locking portion projecting outwardly from such edge, the opening in said attaching portion having an area less than the cross sectional area of said longitudinal edge intermediate the elements, and said locking portion being constituted and consisting of straight equal length end portions of said wire section arranged in contacting side-by-side relation, the combined material of both of such wire end portions being worked to provide a unitary, integral locking portion having a locking projection on one side and

a recess on the opposite side, the said projection and recess being formed in part from each of said wire end portions and being separated by a relatively thin wall formed from the material of both wire end sections, the exterior side surfaces of said locking portion being in substantial alignment with the sides of said attaching portion and forming a continuation of the round exterior surfaces of the latter.
